F. Ledermann

ATTORNEY

UNITED STATES PATENT OFFICE.

HUGO DOERSAM, OF NEW YORK, N. Y.

SAFETY GUARD FOR MACHINE PRESSES.

Application filed August 23, 1923. Serial No. 658,883.

To all whom it may concern:

Be it known that I, HUGO DOERSAM, a citizen of Germany, and resident of New York, in the county of New York and State 5 of New York, have invented certain new and useful Improvements in Safety Guards for Machine Presses, of which the following is a specification.

The main object of this invention is to 10 provide a device to be attached to a punch press to sweep the area above the die for the purpose of removing the fingers from beneath the same, so that no injury may occur if the operator fail to remove his fingers.

Another object is to provide a safety device as mentioned which is operated simultaneously with the tripping or release of the punch press clutch and performs its function before the ram begins its descent, 20 thereby allowing the device ample time in which to remove the fingers from between the punch and die.

These and other objects will become apparent in the description below, in which 25 characters of reference refer to like-named parts in the drawing.

Referring briefly to the drawing, Figure 1 is a front elevational view of the device.

Figure 2 is an end elevational view of the 30 same.

Figure 3 is a sectional end elevational view of the device taken on line 3—3 of Figure 1.

Figure 4 is a side elevational view of the 35 cam plate.

Figure 5 is a front elevational view of the same.

Figure 6 is a partly sectioned elevational 40 view of the gear carrying yoke.

Figure 7 is a front elevational view of a punch press, showing the safety device applied thereto.

Referring in detail to the drawing, the 45 numeral 10 indicates the leg stands of a punch press upon which the table 11 is mounted, the latter supporting the die 12. The crank shaft 13 at the upper end of the press has a fly wheel 14 at one of its ends and is connected to a ram 16 by a connecting rod 15, the ram being slid able behind the 50 guides 17.

A bracket 18 is preferably attached to the left guide at its lower end, said bracket projecting outwardly and having a bifurcated end 19 in which a hole is formed, the latter

receiving a sleeve 20. One end of the sleeve 55 has a U-shaped yoke 21 fixed thereto, the arms 22 of the yoke having holes therein in which a shaft 24 is rotatably mounted. The bifurcated end of the bracket has a screw 25 mounted therein which rigidly secures the sleeve 20 in place in the bracket 18.

A spindle 26 having a sector gear 27 mounted on the end between the arms 22 of the yoke, is rotatably mounted in the sleeve 20. The sector gear 27 meshes with a small 65 pinion 28, the latter being mounted on the shaft 24 above the lower arm 22. The opposite end of the spindle 26 has a bell crank 29 secured thereon by a screw 30. The vertical arm of the bell crank has a pin 31 projecting from its side, the purpose of which will be more fully hereinafter described, and the opposite arm has one end of a rod 32 connected thereto, the lower end of the latter being attached to the foot trip lever 75 33. An angular support 34 rises vertically from the bracket 18 and has a spring 35 secured thereto, the latter being attached to the bell crank 29. A collar 36 having an extension 37, is mounted on the sleeve 20 and 80 has a screw 38 which secures said collar in any desired position. A relatively long sweeper blade 39 having a hole at one end which is slipped over the shaft 24, is mounted on said shaft and is secured in place by 85 a screw 40.

The entire device thus far described is fixed as stated to the left slide guide 17 and is actuated by the rod 32. An additional means for operating the bell crank 29 is 90 provided and comprises a longitudinal bracket 41, the latter being secured to the ram 16. Guide ridges 42 are formed on the face of said bracket. Between these ridges the arm 43 of a cam plate 44 is slid, said 95 arm having a slot 45 therein thru which a screw 46 passes, said screw engaging the bracket 41 and permitting lateral adjustment of the blade 44.

The primary purpose of the entire device 100 is to prevent accidents which would occur when the operator places the work in the gage of the die and by mistake places it in wrong position and tries to save the blank by thrusting his fingers between the punch and die, from which serious injury usually 105 results. The blade 39 is provided to prevent the operator from being able to place

his hand between the punch and the die. Said blade operates in a plane above the die and sweeps across the latter a short time before the punch descends. The sweeping of the blade is accomplished as follows:

- As the trip lever 47 is depressed, the crank shaft clutch is released, thus permitting rotation of the crank shaft 13 and lowering of the ram 16. Simultaneously, the rod 32 on the opposite side of the press is lowered and rotates the bell crank 29 until the screw 30 comes into contact with the extension 37 of the collar 36. As the bell crank is rigidly secured to the spindle 26, the latter will rotate the sector gear 27 which rotates the pinion 28, and consequently, the shaft 24, thereby swinging the sweeping blade 39 above the die thru an arc, carrying everything before it from the surface of the die. When the stroke of the ram 16 is completed, the bell crank will be rotated to its original position by the tension of spring 35.

It sometimes occurs that a punch press gets out of order because the brake becomes loose, permitting the crank shaft to rotate of its own accord; or the clutch may break, or the fly wheel may be locked on the crank shaft owing to lack of lubrication. This device will operate just as well under all such conditions. The greatest danger with punch presses is that they may often repeat their operations of their own accord. As a punch press repeats, the rod 32 is useless and therefore will not operate the bell crank 29 owing to said rod being in its lowered position. To rotate the bell crank, the cam plate 44 is provided. As the ram descends when repeating, the lower angular edge of the cam plate 44 will engage the pin 31 on the bell crank 29 and will rotate the latter, causing the spindle 26 and shaft 34 to function in the usual manner. From this description it is obvious that if the release rod 32 is broken, the cam plate 44 will operate the bell crank to prevent injury to the operator.

Another feature of this device is the mounting of the yoke and sleeve so that they may be readily rotated out of position, as is required when a die-setter is removing or interchanging dies. The yoke may be readily tilted to any angle desired by loosening the screw 25 at the bifurcated ends of the bracket 18, after which the sleeve may be readily rotated out of position.

I claim:

1. A device of the class described comprising a bracket adapted to be fixed to a punch press and having a bifurcated end, a sleeve mounted in said bifurcated end, a yoke fixed on said sleeve, a shaft rotatably mounted in said yoke, means at the lower end of said shaft for sweeping the region above a die, and means for rotating said shaft.

2. A device of the class described comprising a bracket adapted to be fixed to a punch press and having a bifurcated end, a sleeve mounted in said bracket, a U-shaped yoke fixed to one end of said sleeve, a shaft passing thru the arms of said yoke, a sweeper blade at the lower end of said shaft, a gear on said shaft, and means for rotating said gear.

3. A device of the class described comprising a bracket adapted to be fixed to a punch press, a sleeve passing thru said bracket and having a U-shaped yoke at one of its ends, a shaft rotatably mounted in said yoke, a sweeper blade at the lower end of said shaft, a gear on said shaft, a spindle mounted in said sleeve, a sector gear on one end of said spindle meshing with the aforesaid gear, and means for rotating said spindle.

4. A device of the class described comprising a bracket adapted to be fixed to a punch press, a sleeve passing thru said bracket and having a U-shaped yoke at one of its ends, a shaft rotatably mounted in said yoke, a sweeper blade at the lower end of said shaft, a gear on said shaft, a spindle mounted in said sleeve, a sector gear on one end of said spindle meshing with the aforesaid gear, a bell crank at the opposite end of said spindle, and means for rotating said bell crank to rotate said shaft.

5. A device of the class described comprising a bracket adapted to be fixed to a punch press, a sleeve passing thru said bracket and having a U-shaped yoke at one of its ends, a shaft rotatably mounted in said yoke, a sweeper blade at the lower end of said shaft, a gear on said shaft, a spindle mounted in said sleeve, a sector gear on one end of said spindle meshing with the aforesaid gear, a bell crank at the opposite end of said spindle, a pin on said bell crank, a plate secured to the reciprocating ram adjacent said pin, said cam plate being adapted to rotate said spindle, and means for returning said crank to the original position.

6. A device of the class described comprising a bracket adapted to be fixed to a punch press, a sleeve passing thru said bracket and having a U-shaped yoke at one of its ends, a shaft rotatably mounted in said yoke, a sweeper blade at the lower end of said shaft, a gear on said shaft, a spindle mounted in said sleeve, a sector gear on one end of said spindle meshing with the aforesaid gear, a bell crank at the opposite end of said spindle, a pin on said bell crank, a cam plate secured to the reciprocating ram adjacent said pin, said cam plate being adapted to rotate said spindle when engaging said pin, an angular support projecting from said bracket, a spring suspended from said support and secured to one arm of said bell crank, said spring being adapted to

return the bell crank to normal position after the latter has been rotated, and means for limiting the rotation of the bell crank.

7. A device of the class described comprising a bracket adapted to be fixed to a punch press, a sleeve passing thru said bracket and having a U-shaped yoke at one of its ends, a shaft rotatably mounted in said yoke, a sweeper blade at the lower end 5 of said shaft, a gear on said shaft, a spindle mounted in said sleeve, a sector gear on one end of said spindle meshing with the aforesaid gear, a bell crank at the opposite end of said spindle, a pin on said bell crank, a 10 cam plate secured to the reciprocating ram 15 adjacent said pin, said cam plate being

adapted to rotate said spindle, an angular support projecting from said bracket, a spring suspended from said support and secured to one arm of said bell crank, said 20 spring being adapted to return the bell crank to normal position after the latter has been rotated, a collar on said sleeve, an extension on said collar above the bell crank, said extension being adapted to engage the 25 sides of the bell crank to limit rotation of the latter, and means for rotating said bell crank.

Signed at New York, in the county of New York and State of New York, this 7th 30 day of August, A. D. 1923.

HUGO DOERSAM.
